(57) **CLAIM**

The ornamental design for a medical examination table as shown and described.

DESCRIPTION

FIG. 1 is a perspective view of a medical examination table showing my new design;

FIG. 2 is another perspective view thereof;

FIG. 3 is a top view thereof;

FIG. 4 is a left side view thereof;

FIG. 5 is a front view thereof;

FIG. 6 is a bottom view thereof;

FIG. 7 is a right side view thereof;

FIG. 8 is a back view thereof; and

FIG. 9 is a perspective view of the medical examination table showing my new design showing the pull out paper drawer on the left, the fold down step pull out in the middle, and the foot rest pull out on the right;

FIG. 10 is another perspective view showing the step folded down.

FIG. 11 is another perspective view showing the use of the end slot; and,

FIG. 12 is another perspective view showing the bottom scale drawer opened.

The broken lines in the form of a paper roll shown in FIGS. 9-11 depict environmental subject matter and form no part of the claimed design. The broken lines in the form of movement arrows in FIGS. 9 and 10 depict graphical drawing symbols and form no part thereof.

1 Claim, 12 Drawing Sheets
